UNITED STATES PATENT OFFICE

JULENA NUTT, OF TOLEDO, OHIO

DRESS PROTECTOR

Application filed May 19, 1928. Serial No. 278,934.

My invention has for its object to provide a dress protector that may be readily secured on the inside of the back of the dress and so as to cover the shoulder blades of the wearer.

- 5 As is well known, dresses of the present mode are exceedingly thin and formed of very light weight material and without lining of any kind. My invention provides a sheet material so formed that it may be readily re-
10 movably secured in position so as to prevent soiling of the dress and also so as to prevent ripping of the dress when the wearer is exercising or performing any operations with the arms and shoulders, such as driving an au-
15 tomobile, playing tennis, golf, etc. The invention also provides a means whereby the lingerie straps may be maintained in position on the shoulders of the wearer and thus, in the ordinary movements of the body of
20 the wearer, the straps will be held in position without slipping. Consequently, in exercising, the invention is advantageous for preventing displacement of the lingerie straps as well as in protecting the fabric of the dress
25 from becoming soiled from within. The invention thus provides a means for greatly extending the length of time in which the dress may be worn without becoming soiled or torn.
30 The invention may be embodied in dress protectors that vary in their details of outline and means of application and securement to ladies' garments. To illustrate a practical application of the invention, I have selected a protector embodying my invention, as an example of such protectors, and shall describe it hereinafter. The protector selected as an example is shown in the accom-
35 panying drawing.
40 The figure of the drawing illustrates a dress turned inside out and the protector shown partially secured in position.

The protector 1 is formed of a light weight sheet material cut to conform substantially to the back of the dress 2 at a point where the dress covers the shoulder blades. The protector is cut so as to form the curved edge 3 that conforms to the shape of the base of the neck of the dress, such as at the base of a collar, and the curved edges 4 that conform to

the rear of the arm at the shoulder and which ordinarily follows the line of the rear edge of the arm hole of the garment. It is also cut to form a lower edge 5 that extends across the back of the dress about at the points of the shoulder blades and to points below the arm pits. This forms projecting portions 6 and 7 between the edges 4 and 5 that preferably extend to the seams 8 and 9 respectively, to which the projecting portions 6 and 7 are preferably secured by tacking by means of a few stitches 10 at the corners formed between the straight edges 5 and 11 and the edges 11 and 4.

The corners formed between the edges 12 and the edges 3 and 4 are also tacked by means of a few stitches 13 and so that the edges 12 will extend along the top of the shoulders. These corners are also preferably secured at seams or points of juncture between portions of the garment. Thus the protector may be readily secured in position and also may be readily removed and replaced, if desired, by another protector, and moreover, the protector is so formed that it may be connected to the substantial parts of the garment which is usually formed of exceedingly light material. The protector may be formed of a washable material and may be removed and cleansed and replaced.

Short straps 15 located in proximity to the edges 12 may be secured by the tacking as by threads 16 to the garment and snap fasteners having parts 17 and 18 are secured to the ends of the straps 15 and the protector 1. The parts 18 that are secured to the protector 1 are located in proximity to the edges 12. Preferably the straps are secured near the shoulder points or corners between the edges 4 and 12 of the protector, while the parts 18 of the snap fasteners are located substantially midway between the corners formed by the edges 3 and 12 of the protector 1.

The lingerie straps may thus be gathered by insertion of the straps 15 underneath the lingerie straps and the fasteners having the parts 17 and 18 may be snapped and thus secured together, which will maintain the lingerie straps in position on the shoulder of the

wearer notwithstanding the body movements of the wearer.

I claim:

In a dress protector, a fabric cut to conform to the upper portion of the back of the dress that covers the shoulder blades, the protector having edges that conform to the neck opening at the back, and edges that extend to the tops of the shoulders, and edges that extend from the shoulders to points beneath the armpits, and edges that extend along substantially vertical lines below the armpits, and an edge that interconnects the said vertical edges, the protector secured to the said dress portion at the corners formed by the said edges of the protector, the protector located on the inside of the dress, and straps having snap fasteners at their ends and connected to the protector at their remaining ends at points intermediate the neck and the tops of the shoulders whereby the lingerie straps of the wearer may be secured in position.

In witness whereof I have hereunto signed my name to this specification.
